CHARCOAL AND BRIQUET STARTER

Morgan C. Davis, 340 Oak St., Barron, Wis. 54812

Filed July 22, 1969, Ser. No. 18,328

Term of patent 14 years

Int. Cl. D27—05

U.S. Cl. D48—27

FIG. 1 is a view in perspective of a charcoal and briquet starter showing my new design;

FIG. 2 is a view in side elevation, the side opposite that shown in FIG. 2 being substantially a mirror image;

FIG. 3 is a view in top plan; and

FIG. 4 is a view in bottom plan.

I claim:

The ornamental design for a charcoal and briquet starter, as shown and described.
